UNITED STATES PATENT OFFICE.

JOSEF HOFMANN, OF BERLIN, GERMANY.

MOTIVE-POWER APPARATUS.

SPECIFICATION forming part of Letters Patent No. 694,642, dated March 4, 1902.

Application filed April 24, 1901. Serial No. 57,228. (No model.)

To all whom it may concern:

Be it known that I, JOSEF HOFMANN, a subject of the Emperor of Austria-Hungary, residing in Berlin, Germany, have invented an Improved Motive-Power Apparatus, of which the following is a specification.

My invention relates to that class of apparatus in which an expansive motive fluid is produced for use in motors of the character of steam-engines by combustion of an explosive mixture and the combination of the hot gases of combustion with water, which is thereby converted into aqueous vapor.

One of the main objects of my invention is to so construct the apparatus that the whole heat and force of the products of combustion will be utilized in their primary function of combining with the water to produce the expansive fluid in the form of aqueous vapors to be used in the motor.

In the accompanying drawings, Figure 1 is a diagrammatic view, partly in section, illustrating a construction and combination of apparatus for carrying my invention into effect; and Fig. 2 is a view of a modification.

The motor in which the aqueous vapors are to be employed to produce power is represented at *a*, Fig. 1, and may be of any suitable or well-known form. In the drawings I have indicated in plan a four-cylinder engine with a central main crank-shaft *b*. With this motor is combined a pumping appliance *B*, to be actuated from the motor directly or indirectly to draw in and compress a charge of an explosive mixture, which is ignited, and at the forward compression-stroke of the piston of this pump the gases of combustion are discharged to an injector *Z*, which draws in water and sprays it, with the hot gases, into a suitable combining or mixing chamber *7*, whence the expansive motive fluid thus produced is delivered to motor *a* through the pipe *8*.

I prefer to actuate the gas-pump *B* indirectly from the motor *a* through hydraulic means—namely, a pump *c*—which supplies the water required for combination with the hot gases, this water being utilized as a medium for actuating in one direction the piston *k* of the gas-pump *B*. The water afterward passes to the water-jacket *g'*, where it

is heated, and thence through the pipe *w* to a receiver *x* and pipe *y* to the injector *Z*.

The piston-rod *c'* of the pump *c* may be driven from the shaft *b* of the motor *a* in any suitable way, but preferably through the medium of a variable friction-gearing *b'*. The pump *c* draws its water from any suitable supply *d* through a suction-valve *9* on the upstroke of the piston and then on the downward stroke forces its charge out through the outlet-valve *10* and pipe *e* to the hydraulic cylinder *f*, which is mounted centrally in the hollow cylindrical cap *m* of the pump-cylinder *g*. In this cylinder *f* works a ram or piston *l*, fixed to the gas-pump piston *k*, which preferably has a conical face corresponding with the conical end of the cylinder *g*. The latter has the water-jacket *g'* around it. At the outer conical end of this cylinder *g* there is an inlet-valve *h* for the combustible mixture of air and gas or other explosive mixture, and *j* indicates any suitable ignition device. The outlet-valve for the products of combustion is represented at *i*, being normally held to its seat by a spiral spring *6*, acting upon a piston *4*, which is secured to the stem of the valve *i* and which is free to work in the cylindrical casing *5*, but leaving between the valve *i* and piston *4* a chamber *3*, from which leads an outlet-pipe *2* to the injector *Z*. The described construction of valve *i* and piston *4* makes the valve a balanced valve so far as regards back pressure from the pipe *2*.

From the water-pipe *e* there leads a branch pipe *q* to the water-jacket *g'*, the connection, however, being through a valve-box *r* and valve *s*, the stem *t* of which extends into the cylindrical cap *m*, where it passes freely through a cross-head *o* and is provided with shoulders or stops *u* and *v*, to be acted on by the said cross-head at the extremities of its movement. This cross-head *o* is guided on the exterior of the fixed cylinder *f* and is connected by rods *p* to the piston *k*, spiral springs *n* being interposed between the cross-head and the inner end of the hollow cap *m* to draw the piston *k* back to the position shown in the drawings. When the piston is in the backward position illustrated in the drawings, the cross-head *o* will have come against the stop *u* in the valve-rod *t* and pushed the valve

s to the position shown, cutting off communication between the cylinder f and the branch q, leading to the water-jacket g'. On the other hand, when the piston k has been forced 5 outward at the end of its stroke by the pressure of the water in the cylinder or ram f the cross-head o will have come into contact with the stop v on the valve-rod t and will have opened communication between the cylinder 10 f and the branch pipe q.

The operation of the apparatus is as follows: On the downstroke of the piston c' of the hydraulic pump c the pressure of the water will force the piston k of the gas-pump 15 B outward toward the conical end of the cylinder g until the valve s is moved by the forward movement of the piston from the position shown to open communication from the cylinder f to the branch q. Thereupon the 20 piston of the pump c beginning its upstroke the action of the springs n will cause the piston k to return, forcing the water out from the cylinder f through the branch q into the water-jacket g' and thence to the receiver x. 25 This return stroke of the piston k will draw in the explosive mixture through the valve h, and when the piston k reaches the end of its return movement (the position indicated in the drawings) the valve s will be moved to cut 30 off communication between the cylinder f and the branch q, and thereupon the force of the pressure of water by the pump c will force the piston k outward again, compressing the charge of the explosive mixture in the cylinder 35 q, until it reaches a point where it is exploded by the igniting device j. The piston k has, however, not then reached the end of its outward movement, and the force of the explosive action is therefore not expended 40 in returning the piston k. The whole force of the explosive and expansive action is directly utilized for its primary purpose of carrying the gases of combustion out through the valve i and the pipe 2 to the injector Z, 45 where they will by suction draw the hot water from the receiver x. Not only is all the force of the explosive action thus used for its primary purpose, just described, instead of being expended in actuating a piston, as in a gas-engine, but, further than that, the piston k immediately after the explosion will continue its forward movement and at the same forward stroke force out the remainder of the products of combustion 55 through the valve i and pipe 2. When the piston has thereupon reached the extremity of its outward movement, the cross-head o, carried by it, will come into contact with the stop v on the valve-rod t and move the 60 valve s so as to then open communication between the cylinder f and the branch q, leading to the water-jacket, whereupon the springs n, which have meantime been compressed, will draw the piston k back to the position shown, drawing in a fresh supply of combustible mixture through the valved inlet h and then closing the valve s, and so the cycle of

movements will continue. In the vaporizing-chamber, which I prefer to form as a coil 7, the hot gases of combustion exchange their 70 heat with the less hot water sprayed therein by and with the gases from the injector Z, and the hot water is converted into steam, which, mixed with the now-cooled gases, furnishes an expansive motive fluid suitable to 75 operate motors of the character of steam-engines—as, for example, the motor a, to which the mixture is supplied through the pipe 8. The quantity of water mixed with each charge 80 of the gas and the action of the gas-pump may be regulated by proper proportioning of the water-pump c and the cylinder f and by proper regulation of the working speed of the water-pump c.

The described construction of motive-power 85 apparatus on the one hand insures a more complete utilization of the fuel than with a steam-boiler, and on the other hand insures the smooth running of a steam-engine without the jerky vibrations of a gas-engine.

It will be understood that I do not confine myself to the details of construction described, as various modifications may be made therein. For instance, as shown in Fig. 2, there may be interposed between the water-pump c' and the hydraulic cylinder f an accumulator P, the pipe e' from the latter leading to a valve-box r', in which a valve s' is so interposed as to cut off communication between the pipe e' and the cylinder f when the latter is opened to the branch q, as will be readily understood.

I claim as my invention—

1. The combination with a motor of the steam-engine type of a pump for compressing combustible mixtures, means for exploding the mixture before the termination of the compression-stroke and discharging at the same stroke, a valved outlet from said pump, a mixing-chamber to which said outlet leads, means for supplying water with the hot gases of combustion to the mixing-chamber, a pipe leading from the latter to the motor, and means whereby the motor actuates the said pump.

2. The combination with a motor of the steam-engine type, of a pump for compressing combustible mixtures, means for exploding the mixture before the termination of the compression-stroke and discharging at the same stroke, a valved outlet from said pump, a mixing-chamber, means for supplying water with the hot gases of combustion to the mixing-chamber, a pipe leading from the latter to the motor and means to actuate the pump from the motor to compress the combustible mixture and discharge the gases of combustion by the same forward stroke of the pump-piston.

3. The combination with a motor of the steam-engine type, of a pump for compressing combustible mixtures, means for exploding the mixture before the termination of the compression-stroke and discharging at the

same stroke, a valved outlet from said pump, a mixing-chamber, means for supplying water with the hot gases of combustion to the mixing-chamber, a pipe leading from the latter to the motor, and means including a variable friction - gearing for actuating said pump from the motor.

4. The combination of a motor of the steam-engine type, with a pump for drawing, compressing and igniting combustible mixtures, a mixing-chamber, means for supplying water with the hot gases of combustion to the mixing-chamber, a pipe leading from the latter to the motor, and a hydraulic pump to actuate the piston of the gas-pump on its forward stroke, substantially as described.

5. The combination of a motor of the steam-engine type, with means for mixing hot water and gases to produce expansive fluid to actuate the motor, a pump for drawing, compressing and igniting combustible mixtures and discharging the hot gases, a hydraulic pump operated from the motor to supply wa-

ter to actuate the piston of the gas-pump and to supply the water for mixture with the hot gases, substantially as described.

6. The combination of a motor of the steam-engine type, with means for mixing hot gases and water to produce expansive fluid to actuate the motor, a pump for drawing, compressing and igniting combustible mixtures, and discharging the hot gases, a hydraulic pump to supply the water for the mixture, and also to actuate the piston of the gas-pump and a valve actuated by said pump-piston to open and close the connection to the water and gas mixing means, all substantially as described.

In testimony whereof I have signed my name to this specification in the presence of two subscribing witnesses.

JOSEF HOFMANN.
